ELECTRIC SELECTIVE REMOTE CONTROL SYSTEM

Application filed March 25, 1930, Serial No. 438,890, and in Great Britain May 2, 1929.

This invention relates to electric selective remote control systems for a number of circuit-breakers or other apparatus at an electric power substation of the kind in which mechanisms are provided at the substation and the control station and are connected together by pilot wires, whereby an operator at the control station can transmit selecting currents to the substation to cause the selection of the individual circuit-breakers or other apparatus, whilst supervisory indicating currents can be transmitted from the substation to the control station for the purpose of giving an indication of the condition of the selected apparatus, with or without means for transmitting other currents such for example as executive currents for causing the operation of selected substation apparatus, or alarm currents for giving an alarm at the control station in the event of a change occurring automatically in the condition of the substation controlled apparatus, or metering currents for giving meter readings at the control station of the condition of circuits or apparatus at the substation. The term "remote control currents" will hereinafter be employed to designate generally all such currents whether for selecting or indicating or executive or other purposes.

The primary object of the present invention is so to arrange such a remote control system as to enable some of the pilot wires normally employed for carrying remote control currents to be temporarily borrowed without harmful interferences with the system for other purposes, such for example as the transmission of currents in a protective system for a feeder or like circuit.

The electric selective remote control system according to the present invention employs four pilot wires to carry the remote control currents, and is so arranged that the remote control currents passing over either of two of the pilot wires are such that the temporary disconnection of the two pilot wires will not cause incorrect operation of the remote control apparatus. The system is also so arranged that, whenever these two pilot wires are connected together through remote control apparatus at either end, such apparatus

will remain inoperative if temporarily energized from a source of current external to the remote control system. In this manner the two pilot wires are available for temporary borrowing for protective or other purposes. 55

Thus such a remote control system may be employed in combination with protective gear for a feeder or like circuit lying adjacent to the remote control system, devices operated by the protective gear being provided whereby the two borrowable pilot wires are transferred when required from the remote control system to the protective system and are returned to their normal remote control connections as soon as their services are no longer required for the protective purposes. In such a combined arrangement a transfer device is preferably provided at each end of the protective system and when operated acts first of all to disconnect the two pilot wires from the remote control system, one or each of the transfer devices then acting to connect the two pilot wires to a source of E. M. F. associated with the protective system. One protective system, which is especially suitable for such combined service is that described in the United States Patent No. 1,765,887 standing in the names of one of the present applicants and another. 70 75

In order that any interruption from the protective system may not interfere with the process of selection, the transmission of selecting currents from the control station to the substation is conveniently carried out over the two unborrowable pilot wires. For controlling the selecting process, the arrangement forming the subject of United States Letters Patent No. 1,820,354 standing in the names of one of the present applicants and another is preferably employed, wherein the apparatus at the control station controlling the transmission of a selecting current remains locked against further operation when such current has been transmitted until released by a current transmitted from the substation when the apparatus at the substation has correctly performed its selecting movement. This release current may be transmitted over the two borrowable pilot wires to a release relay in the control station, such 80 85 90 95 100

release relay being arranged to be responsive to the release current but to remain unaffected if temporarily energized from the source of E. M. F. associated with the protective system. Thus the protective source of E. M. F. and the source from which the release current is derived may both be D. C. sources, but may be so arranged as to be connected to the two pilot wires with opposite polarities, the release relay being polarized to be responsive only to the release current.

The system is preferably such that as soon as a selecting operation has been performed a circuit is completed over which a current is transmitted from the substation to the control station to give a supervisory indication as to the condition of the selected apparatus. Preferably one of the borrowable pilot wires is utilized in conjunction with one of the unborrowable pilot wires for carrying the supervisory indicating currents. With this arrangement means may be provided whereby, while supervisory indicating currents are flowing in the one borrowable pilot wire, a circuit including the other borrowable pilot wire is prepared over which alarm currents can be transmitted from the substation to give an alarm at the control station in the event of any change occurring automatically in the condition of the controlled substation apparatus. Such means may act on the disconnection of the two pilot wires by a transfer device to open the alarm circuit and thereby to prevent undesired operation of the alarm apparatus from the source of E. M. F. associated with the protective system.

Again means are preferably provided for establishing a clean circuit over the two unborrowable pilot wires for the transmission of metering currents from the substation to the control station. The metering circuit may be established by control station apparatus which causes a current to be transmitted to a time-lag relay at the substation over one of the borrowable pilot wires and one of the unborrowable pilot wires. Conveniently the time-lag relay is connected across the two borrowable pilot wires and a quick-acting relay provided in the substation in series with the borrowable pilot wire utilized for the indicating circuits acts whenever current is flowing in such pilot wire to disconnect the other borrowable pilot wire from the time-lag relay. The control station apparatus which controls the transmission of current to the time-lag relay may be held locked in the event of temporary disconnection of the borrowable pilot wires before the completion of the time-lag of the relay, whereby the normal process of energizing such relay recommences immediately the pilot wires are restored.

The invention may be carried into practice in various ways, but the accompanying drawings illustrate by way of example a con-

venient arrangement according thereto, in which the remote control system is combined with a protective system of the kind described in the prior United States Patent No. 1,765,887, above mentioned.

In these drawings,

Figure 1 is a circuit diagram of the substation apparatus, and

Figure 2 is a similar diagram of the control station apparatus.

In this arrangement the control station and the substation are connected together by four pilot wires A¹ A² A³ A⁴ which will for convenience be referred to respectively as the first, second, third and fourth pilot wires. The first and second pilot wires A¹ A² are so utilized in the remote control system that they can be borrowed temporarily for protective purposes without harmful interference with the remote control system, whilst the third and fourth pilot wires A³ A⁴ are retained exclusively for remote control purposes.

The protective gear now to be described is utilized for the protection of a feeder or like circuit B lying adjacent to the remote control system, such for example as a power feeder connecting the control station and the substation. It will be appreciated that there may be two or more separately protected feeder sections between the two stations, the protective gear for each section being capable of borrowing a portion of the first and second pilot wires A¹ A² when required. For simplicity of description, however, it will be assumed that a single feeder section extends from the control station to the substation.

The apparatus at the substation forming part of the protective gear is, with one exception to be referred to later, identical with that at the control station, and it is consequently only necessary to describe the apparatus at one end. In the drawings small reference letters are used to denote the control station protective apparatus, whilst corresponding capital letters denote the substation protective apparatus.

The protected feeder B is provided at the substation end with two groups of relays, hereinafter referred to as the tripping relays diagrammatically indicated at C and the stabilizing relays diagrammatically indicated at D, each group containing overload and earth leakage relays arranged in the manner described in detail in the prior United States Patent No. 1,765,887 above mentioned. The stabilizing relays D are directional in operation, so that one or other of them will operate on the occurrence of a fault on the network provided that the current at the adjacent end of the feeder B is flowing outwards from the feeder, whilst the tripping relays C operate on the occurrence of a fault on the network irrespective of the direction of current flow in the feeder. The operation of any one of the stabilizing

- relays D causes the operation of a stabilizing auxiliary relay E, and similarly the operation of any one of the tripping relays C causes the operation of a tripping auxiliary relay F. The tripping auxiliary relay F has two sets of change-over contacts $F^1 F^2$ which in their normal position connect the first and second pilot wires $A^1 A^2$ to their normal remote control circuits, but after operation of the relay disconnect them from such circuits and connect them respectively to two sets of change-over contacts $E^1 E^2$ on the stabilizing auxiliary relay E, and thence, if the stabilizing auxiliary relay has not operated, to the operating coil of a lock-out relay G or, if the stabilizing auxiliary relay has operated to the two sides of a local battery H forming part of the protective gear. The normally closed contacts G^1 of the lock-out relay G in series with normally closed contacts E^3 on the stabilizing auxiliary relay E and normally open contacts F^3 on the tripping auxiliary relay F control a circuit from the local protective battery H to a time-lag relay J directly controlling the tripping circuit K for the circuit-breaker L at the adjacent end of the feeder B.
- Thus under normal conditions the first and second pilot wires $A^1 A^2$ are connected at both ends through the tripping auxiliary relay contacts $F^1 F^2 f^1 f^2$ to their remote control circuits. On the occurrence of a fault on the network external to the protected feeder B, a heavy straight-through current will flow in one direction through the feeder from end to end. This will cause the operation of the tripping auxiliary relays F f at both ends and of the stabilizing auxiliary relay E at one end—say, the substation end. Thus the first and second pilot wires $A^1 A^2$ will be connected at the control station end to the lock-out relay g and at the substation end to the local protective battery H, so that a stabilizing current will flow from the substation to operate the control station lock-out relay g and thereby prevent operation of the time-lag relay j at that station. Operation of the substation time-lag relay J will at the same time be prevented by the operation of the substation stabilizing auxiliary relay E at contacts E^2 , so that the feeder B will remain in circuit at both ends. As soon as the fault is cleared the tripping and stabilizing auxiliary relays will reset themselves and return the pilot wires $A^1 A^2$ to their normal remote control circuits. In the event of a fault on the protected feeder B itself, in which the fault current is fed from both ends of the feeder, both tripping auxiliary relays F f will operate, but the stabilizing auxiliary relays E e will remain inoperative, and the time-lag relays J j will operate to cut out the feeder B at both ends. The tripping auxiliary relays F f will reset themselves as soon as the feeder is cut out and

will return the pilot wires $A^1 A^2$ to their normal circuits. In the case of a fault supplied from one end only, only the tripping auxiliary relay F or f at the supply end will operate, the other relays remaining inoperative. Thus the two pilot wires $A^1 A^2$ will be disconnected from the remote control circuits at one end only, but will be connected up again as soon as the feeder is cut out at the supply end.

It will be appreciated that since the relays at the two ends operate independently, it may happen that those at one end may operate first, so that for a very brief interval, the lock-out relay G or g or the local protective battery H or h at one end may be connected at one end may be connected through the two pilot wires $A^1 A^2$ to the remote control apparatus at the other end. This cannot have any harmful effect on the operation of the protective system, unless it happens that at the moment a battery in the remote control system is connected across the pilot wires $A^1 A^2$. In such a case it might happen that this battery would cause incorrect operation of a lock-out relay, which would delay (or in the case of a fault fed from one end only even prevent) the cutting out of the feeder if faulty. To guard against this, the protective and remote control batteries at each end may be arranged so that they can only be connected to the two pilot wires with opposite polarities, the lock-out relays being polarized to be responsive only to current from the protective battery. As will be clear later, the particular remote control system to be described is such that the control station battery can never be connected across the first and second pilot wires $A^1 A^2$, whilst it is possible for the substation battery under certain circumstances to be connected across them. Consequently it is desirable to polarize the lock-out relay g at the control station end of the protective system, but it is unnecessary to polarize the lock-out relay G at the substation end.

Before describing in detail the arrangement of the remote control system, a brief description will be given of the general nature of the system. A robust mechanical rotary selector is employed at the substation, which has a series of positions each associated with an individual substation apparatus, such for example as a switch or circuit-breaker, and also with a metering source, such as a current transformer, of which meter readings are to be taken at the control station. The rest of the substation equipment is common to all the controlled apparatus, as also is the whole of the control station equipment with the exception of individual meters to be selectively associated with the corresponding substation metering sources. The connections to the meters at the control station are controlled by a mechanical rotary selector which also coop-

erates with indicating mechanism for giving selective indications at the control station of the condition of selected substation apparatus. The two selectors have corresponding 5 step-by-step movements imparted to them, and each selecting movement consists of the movement of the selectors from any one selected position into the next. Each selecting movement is initiated by operation of a single selecting switch of the push-button type at the control station. In order to ensure accurate correspondence of movement between the two selectors, the arrangement described in the United States Letters Patent 10 No. 1,820,354 above mentioned is employed, wherein the control station selector makes two half-notch movements for each full-notch movement of the substation selector during each selecting movement. Thus when the 15 selecting push is operated in any selected position, the control station selector makes its first half-notch movement under the control of solenoid operated ratchet mechanism and a selecting current is transmitted to the substation which through solenoid operated ratchet mechanism causes the substation selector to perform its full-notch selecting movement into the next selected position. As 20 soon as the movement of the substation selector is completed, a release current is transmitted to the control station to energize a release relay and thereby to operate a second solenoid which releases the control station controlling apparatus (which has meanwhile 25 remained locked with the selector in its half-notch position) and subsequently causes the control station selector to perform its second half-notch movement. This completes the 30 selecting movement and the equipment comes to rest again in its new selecting position. The completion of the selecting movement at both ends automatically causes a supervisory indicating current to be transmitted to the control station to operate the indicating 35 mechanism to give an indication at the control station of the condition of the newly selected substation apparatus. At this stage the operator may again operate his selecting push to select the next substation apparatus 40 and obtain a supervisory indication, and so on throughout the cycle.

In any selected position, the operator may, if he wishes, instead of performing a further selecting movement, operate an executive 45 hand-push for causing some operation to be performed on the selected substation apparatus (such as closing or tripping a selected switch or circuit-breaker) or he may operate a meter switch for causing the establishment 50 of the metering circuit over which meter readings can be taken at the control station of the metering source associated with the selected position. Depression of an executive push causes an executive current to be transmitted 55 over the same circuit as the selecting currents,

but with a polarity opposite to that of a selecting current, a polarized relay in the substation effecting the necessary discrimination between the two kinds of current. When the executive function has been performed 70 in the substation by suitable apparatus, the supervisory indicating circuit is reestablished and an indication of the changed condition of the substation apparatus is obtained at the control station, the whole system again coming to rest in a condition ready for a new selecting movement or the establishment of the metering circuit. If now, the operator 75 operates his meter switch (for instance by a rotary movement through 180°) suitable apparatus will cause the establishment of the metering circuit from the selected substation metering source to the corresponding control station meter, and the system will remain 80 at rest in the metering condition, until the meter switch is again operated (for instance by a continued rotary movement through a further 180°) when the system will revert 85 to its normal rest condition in the selected position with the supervisory indicating circuit completed.

The normal zero position of the selectors is reserved for special purposes, such as the establishment of telephone communication 95 between the two stations and the transmission from the substation of a general alarm current to indicate that some change has taken place automatically in the condition of the substation controlled apparatus. Provision is also made for the transmission of a 100 general alarm current in other selected positions in order that the control station operator may be advised of an automatic change for instance while he is taking a meter reading. When a general alarm current is received in the normal zero position, it preferably causes a complete selecting and indicating cycle to be performed (the indicating mechanism being of the self-recording type), so that by the time the operator has come 105 to attend to the general alarm signal he will see the condition of all the substation apparatus and will at once know of the automatic change which brought about the general alarm signal. The automatic reindicating cycle is not however performed in the event 110 of the general alarm signal being transmitted whilst the selectors are in any position other than the normal zero position.

Although primarily the system is such that each selecting movement is initiated by a separate depression of the selecting push, means are preferably provided whereby the operator may effect "express selection", i. e. movement through a number of selected positions without repeated depression of the selecting push. Such express selection consists in the automatic initiation of a further selecting movement immediately a previous one is completed as far as the desired selected posi- 120

tion, the supervisory indications being momentarily given as the various selected positions are passed through.

The system will now be described in detail with reference to the drawings, taking first of all the substation equipment. In the drawings the system is shown at rest in the normal zero position.

In the drawings one controlled circuit-breaker 10 is shown at the substation, namely that associated with the second selected position, but it will be appreciated that there will in practice be a number of such circuit-breakers or other apparatus each associated with an individual selected position. The circuit-breaker 10 is shown open by way of example, and is provided with a closing coil 11, a tripping coil 12, and six auxiliary switches 13-18 which are operated by the movement of the circuit-breaker from its open to its closed position or vice versa. The auxiliary switch 15 is a late-acting switch which is closed when the circuit-breaker 10 is open and opens just before the circuit-breaker closes. The auxiliary switch 16 is a "flick" switch, i. e. one which closes momentarily and opens again during the closing or opening movement of the circuit-breaker 10. The second selected position is also associated with a metering source, indicated by way of example as a current transformer 19.

The substation rotary selector is indicated at 20 and is driven through its step-by-step movements by ratchet mechanism operated by a solenoid 21. Contacts 22-25 are provided which are operated by the selector actuating mechanism during each selecting movement in such a manner that the contacts 22, 24 are closed and the contacts 23, 25 opened immediately the selector completes its movement into a new selected position, the four contacts being brought back again to the condition shown when the selector solenoid 21 is deenergized and its mechanism resets. These contacts control the transmission to the control station over the pilot wires A¹ A² of the release current above mentioned. The selector 20 has groups of contacts associated with its various positions. Thus the contacts 30-37 are associated with the normal zero position and are changed over from the condition shown as soon as the selector leaves this position. These contacts reassume the condition shown when a complete selecting cycle has been performed and the selector again returns to the zero position. The contacts 40-47 are associated with the second selected position (i. e. with the particular circuit-breaker 10 and current transformer 19 shown in the drawings, and are changed over when the selector moves into the second position. These contacts remain in the condition shown in all selector positions other than the second. Similar groups of contacts (not shown) are provided on the selector for

other selected positions. These groups of contacts together with the corresponding circuit-breaker auxiliary switches control the connections between busbars common to all the controlled apparatus and a battery 50 provided in the substation for the operation of various parts of the remote control equipment. The connections to the two poles of the battery are controlled respectively by contacts 55, 56 on a lock-out switch 57, which also has contacts 51, 52, 53, 54 respectively controlling the four pilot wires A¹ A² A³ A⁴ at the substation end, whereby the substation remote control equipment can be cut off from the pilot wires and the battery for inspection and repair purposes.

The positive pole of the battery 50 is connected through the lock-out contact 56 to the positive busbar 60, and the negative pole is connected through the contact 55 to the negative busbar 61 and also to the selector contacts 40, 41, 42, which are closed only in the selected position. The contacts 40 are connected on the other side to the circuit-breaker closing coil 11 and thence to a closing busbar 65, the contacts 41 being similarly connected through the circuit-breaker auxiliary switches 13 and 14 respectively to a close relay busbar 67 and a trip relay busbar 68, whilst the contacts 42 are connected through the trip coil 12 to a tripping busbar 66 and through the auxiliary switch 15 to an executive relay retaining busbar 69. The positive busbar 60 is connected to the flick switch 16 and thence either through the selector contacts 44 (closed in all positions except the selected position) to a general alarm busbar 70 or through the selector contacts 43 (closed only in the selected position) to an auxiliary general alarm busbar 71. The selector contacts 45, 46 (closed only in the selected position) control the connections from two indicating busbars 75, 76 to the contact arms of the circuit-breaker auxiliary change-over switches 17, 18 and thence to one or other of the positive and negative busbars 60, 61, the two indicating busbars thus being oppositely energized with a polarity dependent on whether the selected circuit-breaker is closed or open. The selector contacts 47 are closed only in the selected position and are in series with the metering source 19 between two metering busbars 77, 78. The connections of these busbars to the other parts of the remote control equipment will be described later.

The principal relays in the substation remote control equipment are an executive relay 80 with contacts 81-85 controlling the performance of executive functions; a selector relay 90 with contacts 91-94 controlling the operation of the selector 20; a polarized relay 100 having contacts 101 and 102 respectively controlling the energization from the substation battery 50 of the selector relay and the executive relay, this polarized re-

lay being energized by currents of one polarity or the other sent from the control station over the third and fourth pilot wires A^3 A^4 ; two meter relays 110, 120 respectively with 5 contacts 111—117 and 121—129 for controlling the establishment of a metering circuit, the normally open contact 128 being arranged to close before the opening of the contact 127 when the relay is energized; an auxiliary in- 10 dication relay 130 with contacts 131, 132 whose function will be described later; a release meter relay 135 with contacts 136—138, of which the normally open contacts 137 are arranged to close before the opening of contact 138 when the relay is energized; a trip relay 140 with contacts 141—144 and a close relay 145 with contacts 146—148 operated by the executive relay 80 for controlling the tripping and closing of selected circuit 15 breakers; and a general alarm relay 150 with contacts 151—155 having associated with it a definite time limit relay 156 with its contact 157 for controlling the transmission of general alarm signals to the control station. 20

25 The substation is also provided with a telephone 160 having the usual receiver hook switch 161 and calling bell 162 and with a telephone push 165 having contacts 166—168 for controlling the transmission of a telephone calling current to the control station. The telephone push 165 is locked against operation in all selector positions other than the normal zero position by an electromagnetic locking device 169 energized over a circuit including the selector contacts 30 which are closed in all positions except the zero position. The indicating circuit and the metering circuit (to be described later) are utilized in the normal zero position for carrying the telephone calling signal from the substation to the control station and the telephone speaking currents, the general alarm signal (which is of opposite polarity to the telephone calling signal) also being transmitted over the indicating circuit in this position. For this purpose, the telephone push contacts 167, 168 are arranged as change-over contacts in series with the selector contacts 33, 34 (closed only in the zero position) and 30 control the connections of the indicating busbars 76, 75 to the positive and negative busbars 60, 61 in a manner similar to that of the circuit-breaker auxiliary switches 17, 18, whilst the telephone 160 is in series with the selector contacts 37 closed only in the zero position between the two metering busbars 77, 78. 50

55 The indicating busbar 76 is connected through the normally closed contacts 93 and 127 of the selector relay 90 and the second meter relay 120 and the lock-out contact 54 to the fourth pilot wire A^4 . The other indicating busbar 75 is connected, when the selector is in any position other than the zero position, through the selector contacts 31 and the normally closed contact 124 on the

second meter relay 120 to one side of the auxiliary indication relay 130, the other side of which is connected through the contact 25 on the selector actuating mechanism, the lock-out contact 52 and the contact F^2 of the protective tripping auxiliary relay F to the second pilot wire A^2 . The connection between the second and fourth pilot wires A^2 , A^4 through the indicating apparatus at the control station will be described later. It 70 will be noticed that whenever indicating currents are flowing over this indicating circuit the auxiliary indication relay 130 will be energized. The connection of the indicating busbar 75 to the auxiliary indication relay 130 when the selector is in its normal zero position is taken through the selector contacts 32 and thence, if the telephone push 165 is depressed, through its contact 166, or, if the general alarm relay 150 has operated, through its contact 152, but the circuit is incomplete in the normal zero position unless either the telephone push or the general alarm relay has been operated. The operation of the general alarm relay 150 also closes contact 90 and thus completes a connection from the indicating busbar 75 to the first pilot wire A^1 (through contacts 23, 51 and F^1) provided that either the auxiliary indication relay 130 is energized to close its contact 132 or the second meter relay 120 is energized to close its contact 125. 95

100 The metering busbar 78 is directly connected to the fourth pilot wire A^4 through the lock-out contact 54. The metering busbar 77 is connected to the third pilot wire A^3 through the normally closed contacts 81, 151 and 111 respectively on the executive relay, the general alarm relay and the first meter relay and through the contact 121 (which is closed when the second meter relay operates) and the lock-out contact 53. The manner in which the second meter relay 120 is energized to complete the metering circuit at contact 121 will be described later. 110

115 The polarized relay 100 is connected between the third and fourth pilot wires A^3 A^4 through the lock-out contacts 53, 54 and the contacts 127 and 136 on the second meter relay and the release meter relay, and is consequently capable of receiving currents of either polarity sent from the control station over these pilot wires for selecting or executive purposes. Thus when a selecting current is received the polarized relay will close its contacts 101 and energize the selector relay 90, which breaks the indicating circuit at contact 93 and completes the energizing circuit to the selector solenoid 21 at contact 92. An executive current on the other hand will cause the energization at contacts 102 of the executive relay 80. The function performed by the executive relay depends upon the position occupied by the selector at the time and also on the condition of the selected appara- 120 125 130

tus. Thus if the selector is in a position associated with a circuit-breaker, the executive relay will act at contact 84 to energize either the trip relay 140 or the close relay 145 in accordance with whether the selected circuit-breaker is closed or open, whilst if the selector is in its zero position the executive relay will act at contact 83 to energize the second meter relay 120, and thereby to establish the metering circuit at contact 121 for telephone speaking and to close the telephone calling circuit at contact 122, this calling circuit including the bell 162, the hook switch 161 and the selector contacts 36.

When the executive relay 80 is operated for circuit-breaker closing purposes, it completes its own retaining circuit at contact 85. This circuit is taken from the negative pole of the battery 50 through the lock-out contact 55, the selector contacts 42 in the appropriate selector position, the late-acting auxiliary switch 15 on the selected circuit-breaker 10 (assumed to be open), the retaining busbar 69, the trip relay contact 144, the selector relay contact 94 and the executive relay contact 85 to one side of the operating coil of the executive relay, the other side of which is directly connected to the positive pole of the battery 50 through the lock-out contact 56.

Thus the executive relay retains itself energized independently of the polarized relay 100 until the retaining circuit is broken by the late-acting auxiliary switch 15 when the closing movement of the selected circuit-breaker is completed. The retaining circuit is unnecessary for circuit-breaker tripping purposes owing to the very short time required to complete the tripping operation.

The energizing circuit of the trip relay 140 is taken from the positive pole of the battery 50 through the lock-out contact 56, the executive relay contact 84 and an interlock contact 148 on the close relay 145 to one side of the trip relay coil, the other side of which is connected to the trip relay busbar 68 and thence through the auxiliary switch 14 of the selected circuit-breaker 10, the corresponding selector contact 41 and the lock-out contact 55 to the negative pole of the battery 50.

The energizing circuit of the close relay 145 is taken from the positive pole of the battery 50 through the lock-out contact 56, the executive relay contact 84 and an interlock contact 142 on the trip relay 140 to one side of the close relay coil, the other side of which is connected to the close relay busbar 67 and thence through the auxiliary switch 13 on the selected circuit-breaker 10, the corresponding selector contact 41 and the lock-out contact 55 to the negative pole of the battery 50. Thus when the executive relay 80 is operated in a selected position either the trip relay 140 or the close relay 145 will be energized in accordance with whether the selected circuit-breaker 10 is closed or open. The trip relay 140 makes its own retaining circuit at contact 143 to prevent its deenergization (and the consequent energization of the close relay 145 if the executive relay is still energized) when the circuit-breaker is tripped and the auxiliary switches 13, 14 change over, the close relay 145 being provided with a retaining contact 147 for a similar purpose. The trip relay 140 has a further contact 141 which controls the energization of the circuit-breaker trip coil 12 through a circuit from the battery 50 through the lock-out contact 56, the tripping busbar 66, the trip coil 12 of the selected circuit-breaker 10, the corresponding selector contacts 42 and the lock-out contact 55 to the battery 50. The close relay 145 at its contact 146 energizes the closing coil 11 of the selected circuit-breaker over a similar circuit including the closing busbar 65 and the selector contacts 40 instead of the tripping busbar 66 and the selector contacts 42.

The first meter relay 110, which has a short time lag, is connected on one side to the first pilot wire A¹ through the normally closed contacts 131 and 123 on the auxiliary indication relay and the second meter relay and on the other side to the second pilot wire A² through the operating coil of the auxiliary indication relay 130 (these connections also including the contacts 23, 25 on the selector actuating mechanism, the lock-out contacts 51, 52 and the protective tripping auxiliary relay contacts F¹ F²). Thus so long as indicating currents are flowing in the second pilot wire A², this meter relay is cut out of circuit by the auxiliary indication relay contacts 131. The opening of the second pilot wire circuit and the temporary connection of the first and fourth pilot wires together at the control station whilst the indicating currents are flowing (which as will be explained later is the procedure adopted for the establishment of a metering circuit in a selected position) will deenergize the auxiliary indication relay 130 and divert the indicating currents through the first meter relay 110, and thus cause this relay to close its contact 115 and energize the second meter relay 120 over a circuit including the contact 138 of the release meter relay 135. The relay 120 makes its own retaining circuit at contact 128 and at contacts 123, 124 and 127 opens the normal energizing circuit of the first meter relay 110, which however remains energized through its bridging contacts 112, 113, 116 until the circuit is broken at the control station end. The closing of contacts 111 and 121 completes the establishment of the metering circuit at the substation end, whilst the contacts 117, 129 prepare the circuit for the release meter relay 135 for operation when metering is finished.

The general alarm relay 150 is connected between the general alarm busbar 70 and the negative busbar 61 and is consequently en-

ergized whenever a circuit-breaker 10 changes its condition (owing to the momentary closing of the flick switch 16) unless the selector is in the position corresponding to such circuit-breaker, the selector contacts 44 being then open. If metering is in progress in any selector position when the circuit-breaker associated with such position changes its condition automatically, the general alarm relay 150 will be energized over a circuit from the positive busbar 60, through the flick switch 16, the selector contacts 43, the auxiliary general alarm busbar 71, the second meter relay contact 126 (now closed) and the general alarm relay 150 to the negative busbar 61. The general alarm relay makes its own retaining circuit at contact 154 through the contact 157 of the definite time limit relay 156, which is simultaneously energized at contact 153 over a circuit including interlock contacts 114, 91 and 82 on the first meter relay, the selector relay and the executive relay. The definite time limit relay 156 acts to open the circuit of the general alarm relay after a predetermined time interval. The object of this is to put the general alarm relay 150 in readiness for transmitting a further general alarm signal if necessary in the event of the system being at rest in any position other than the normal zero position, for example whilst metering is in progress.

The control station remote control equipment will now be described.

The supervisory indicating currents, which are transmitted from the substation over the second and fourth pilot wires $A^2 A^4$, are received by a polarized indication relay 200, which is connected between these two pilot wires through certain interlock contacts later to be described. This relay 200 operates one or other of two sets of contacts 201, 202 in accordance with the polarity of the indicating current received and thereby energizes either a positive coil 210 or a negative coil 215 respectively operating contacts 211-213 and 216-218. Although indicated on the drawings as separate relays, these two coils 210, 215 preferably act on a common armature whose movement in one direction or the other operates suitable indicating mechanism which may for instance take one or other of the forms described in the United States Letters Patent No. 1,820,354 standing in the names of one of the present applicants and another. A contact indicated at 205 is operated by the indicating mechanism when the desired indication has been given. The constructions of indicating mechanism described in the prior United States patent referred to include in addition to the common armature of the coils 210, 215 a group of indicators respectively corresponding to the individual substation circuit-breakers 10 or other apparatus, and the determination as to which circuit-breaker has been selected (and

therefore as to which indicator shall be operative) is mechanically effected by a rotary selector indicated at 220 to which step-by-step movements are imparted corresponding to those of the substation selector 20. As will be described in detail later the selector 220 performs two separate half-notch movements for each full-notch movement of the substation selector 20 in the manner described in the United States Patent No. 1,820,354 above mentioned, the first half-notch movement being controlled by a first motion solenoid 221 and the second half-notch movement by a second motion solenoid 222, which is in turn controlled by a polarized release relay 223 having contacts 224. The selector 220 has groups of contacts 230-232, 233 . . . which are operated in its various positions. Thus the contacts 230 are closed in the first few (say four) selector positions and are open in all other positions; the contacts 231 are closed in the normal zero position and open in all other positions; the contacts 232 are closed in all positions other than the normal zero position; the contacts 233 are closed only in the second position. The selector also carries a cam indicated at 225, which operates a contact rod 226 having contacts 227, 228, the arrangement being such that the contacts 227, 228 are open in the first few positions and close before the contacts 230 open, remaining closed from, say, the third position to the last position. The selector actuating mechanism operated by the solenoids 221, 222 also serves to operate contacts 240-248 at various stages in the sequence of operations constituting a selecting movement from one position to the next, as will be described in detail later.

A local battery 250 is provided in the control station, the connection to its two terminals being controlled by contacts 255, 256 on a lock-out switch 257 also having contacts 251, 252, 253, 254 respectively controlling the connections of the four pilot wires $A^1 A^2 A^3 A^4$ to the control station remote control equipment, the general arrangement being similar to that of the lock-out switch 57 at the substation. The positive pole of the battery 250 is connected through the lock-out contact 255 to a positive busbar 260 and the negative pole is connected through the contact 256 to a negative busbar 261. A metering busbar 262 is also provided in the control station, to which are connected the various meters corresponding to the metering sources in the substation, the other sides of the meters being connected through selector contacts to the positive busbar 260. One such meter 265 in series with the selector contacts 233 is shown by way of example in the drawings.

The performance of a selecting movement of the two selectors 20, 220 is initiated at the control station by depression of a selecting push 270 having contacts 271, 272, 273, 274.

This push is of special construction to enable it either to be depressed and released for the purpose of initiating a simple selecting movement from one position to the next or to be depressed and rotated (whereby it is held in the depressed condition until released by a return movement) for the purpose of initiating an "express" selecting movement through a series of successive simple selecting movements from any one position to any other position. The contacts 271, 273, 274 are operated by depression of the push and remain in their operative positions when the push is rotated, whilst the contact 272 remains inoperative unless the push is rotated.

The performance of executive functions in the substation in any selected position is initiated by means of a trip push 280 and a close push 290, which have similarly arranged contacts 281-285 and 291-295 respectively. The contacts 281, 282, 285 or the contacts 291, 292, 295 serve when the corresponding push is operated to break the normal connections of the pilot wires $A^1 A^2 A^4$, all of which are normally connected directly or indirectly to the positive busbar 260, whilst the contacts 284, 294 serve to make a connection from the negative busbar 261 through the contact 244 on the selector actuating mechanism to the pilot wire A^4 , and the contacts 283, 293 make a similar connection from the positive busbar 260 through the selector actuating mechanism contact 243 to the pilot wire A^3 .

The establishment of a metering circuit in any selected position is initiated at the control station by a rotary meter switch 300 having contacts 301-309. This meter switch may be constructed and arranged in a manner similar to that described in British Patent No. 310,984. Contacts 301, 306 and 309 are normally closed and control the normal connections to the pilot wires $A^1 A^2$ and A^4 respectively. To establish the metering circuit the switch 300 is rotated through 180° . The first movement of the switch opens contacts 301 and 306, and shortly afterwards, say at about 90° rotation, the contact 303 closes for a brief interval and opens again. Contact 304 opens approximately at the 120° position. When the 180° position is reached the contacts 302 and 308 close, the contact 308 making a direct connection from the metering busbar 262 through the lock-out contact 253 to the third pilot wire A^3 . The other side of the selected meter is connected through part of the positive busbar 260 to the fourth pilot wire A^4 through various closed contacts including the contact 309. When it is desired to open the metering circuit, the meter switch 300 is rotated further, its first action being to disconnect the selected meter from the pilot wires by opening contacts 308 and 309, contact 302 also being opened. At or about 270° the contacts 305, 307 are closed and opened, the contact 305

serving to make a connection from the negative busbar 261 through contact 244 to the second pilot wire A^2 whilst the contact 307 connects the positive busbar 260 through contact 243 to the third pilot wire, whereby a momentary current is transmitted over these pilot wires to the substation for the energization of the release meter relay 135. The completion of the 360° movement of the meter switch recloses contacts 301, 304, 306, 309 and thus brings the circuits back to the normal condition.

As will be explained in detail later the temporary closing of the contact 303 at the 90° position causes the energization of the first meter relay 110 at the substation and since this relay has a slight time-lag it is necessary to arrange that the contact 303 remains closed for a sufficient time. For this purpose an auxiliary meter relay 310 is provided in series with the contact 303, the normally open contact 311 of this relay controlling the energizing circuit of a time-lag electromagnetic locking device 315 acting on a projection diagrammatically shown at 316 on the meter switch 300, the arrangement being such that the lock is normally applied and is released when the coil 315 has been energized for a time interval equal to the time-lag of the substation first meter relay 110. This locking device is provided with a contact 317 in series with the meter switch contact 304 to retain the coil 315 energized until the meter switch has passed the 120° position.

The establishment of telephone communication between the two stations is initiated by a dummy push 320 operated by lifting the telephone instrument. This push has contacts 321-326, two of which 322, 326 are normally closed and control the connections to the pilot wires $A^2 A^4$. The first movement of the dummy push 320 opens these two contacts 322, 326, shortly after which the contacts 324, 325 close and open again to transmit a momentary current from the control station battery over the pilot wires $A^3 A^4$ similar to that transmitted by the operation of the trip and close pushes. The completion of the movement of the push 320 closes contact 323 and recloses contact 326, thereby connecting the telephone instrument 330 across the pilot wires $A^3 A^4$ through various closed contacts including a contact 341 on a zero position relay 340, which is energized through the selector contacts 231 closed only in the normal zero position. During the return movement of the dummy push 320, after the telephone conversation has been completed, the contacts go through the reverse movements with the exception that contact 325 is inoperative and contact 321 (which was inoperative during the forward movement) closes and opens simultaneously with contact 324.

The zero position relay 340 has in addition

- to the contact 341 four other contacts 342-345, all of which are closed when the relay is energized, i. e. when the selector is at rest in the zero position. The telephone buzzer 331, with which a red lamp 332 is in parallel, is energized when the polarized relay 200 causes the positive coil 210 to close its contact 212, this energizing circuit including the contact 344 on the zero position relay 340.
- 10 The energization of the positive coil simultaneously opens contact 211 and thereby breaks a normally closed circuit, including contacts 216 and 342, to a green lamp 333. The buzzer 331 and red lamp 332 are also utilized for giving the general alarm signal under the control of two general alarm relays 350, 355, the contact 356 of the latter relay directly controlling the buzzer circuit. The main general alarm relay 350 is connected between the first and fourth pilot wires A¹, A⁴ through various contacts, this connection being completed in various circumstances by the contacts 213, 218 and 302. Thus when the system is at rest in the normal zero position the contact 218 closes to complete this connection when the polarized relay 200 receives a general alarm signal, and similarly when the system is in any other selected position and a supervisory indicating current is flowing one or other of the contacts 213, 218 will be closed in accordance with the polarity of the indicating current, whilst when a metering circuit is established in any position the contact 302 will be closed.
- 30 This general alarm relay 350 is energized by a general alarm signal transmitted from the substation over the pilot wires A¹, A⁴, and its contact 351 controls the energizing circuit of the auxiliary general alarm relay 355, 40 which besides closing the contact 356 in the buzzer circuit makes at contact 357 its own retaining circuit through a normally closed contact 337 on a stop alarm push 335 having a further contact 336 and through a normally closed contact 365 on an auxiliary reindication relay 360. This relay 360 has four other contacts 361-364 and its energizing circuit is controlled by the contact 371 of a general reindication relay 370 having other contacts 50 372-374.
- 55 The two reindication relays 360, 370 are utilized for causing a complete selecting and indicating cycle to be performed automatically when a general alarm signal is received from the substation while the system is at rest in the normal zero position, and it is necessary for this purpose for the indicating mechanism controlled by the positive and negative coils 210, 215 to be of the self-recording type. The reception of a general alarm signal under these circumstances causes contact 217 to close and thereby to complete a circuit through the contact 343 to the general reindication relay 370, which makes its own retaining circuit at contact 372

through the selector contacts 230 which are closed in the first four selector positions. Contacts 373, 374 respectively bridge the selecting push contacts 273, 274, and contact 371 completes the circuit to the auxiliary relay 360. This relay makes its own retaining circuit at contact 361 through the selector contacts 232 closed in all positions except the zero position, and also through a further circuit including the selector push contact 271 and the stop alarm push contact 336. The contact 365 opens to deenergize the auxiliary general alarm relay 355 and the contacts 363, 364 in series with the cam-operated contacts 227, 228 makes further bridging connections across the selecting push contacts 273, 274 after the third position is reached.

70 The operation of the remote control system will now be described first of all with reference to the performance of a selecting movement from one selector position to the next. When the system is at rest in the normal zero position as shown all the remote control equipment is deenergized with the exception of the zero position relay 340, which is energized over a circuit from the control station positive busbar 260, through the contact 243 on the selector actuating mechanism, the relay 340 and the selector contacts 231 to the negative busbar 261.

75 On the other hand when the system is at rest in any other position, a supervisory indicating current is flowing over the indicating circuit which is taken (assuming for example that the selectors are in the second position corresponding to the open circuit-breaker 10 shown in the drawings) from the substation negative busbar 61 through the circuit-breaker auxiliary change-over switch 17, the substation selector contacts 45, the indicating busbar 75, the selector contacts 31 (now closed), the contact 124, the auxiliary indication relay 130, the contacts 25, 52, F², the pilot wire A², the contacts f², 252, 282, 292, 306, 322, the polarized indication relay 200, the contacts 241, 326, 309, 295, 285, 254, the pilot wire A⁴, the contacts 54, 127, 93, the indicating busbar 76, the selector contacts 46 and the auxiliary change-over switch 18 to the positive busbar 60. Thus the auxiliary indication relay 130 is energized, and the polarized indication relay 200 is also energized to close its contacts 202, whereby the indicating mechanism is giving the correct "out" indication and the contacts 216, 217, 218 and 205 are operated. The rest of the equipment is deenergized.

80 85 90 95 100 105 110 115 120 125 130 135 If now it is desired to effect a selecting movement from one position to the next, the selecting push 270 is depressed to close contact 274. This completes the circuit to the first motion solenoid 221 from the negative busbar 261, through the selector actuating mechanism contact 248, the solenoid 221 and

the selecting push contact 274, and thence either through the contact 345 or the contact 205 (according to whether the selectors are in the zero or in any other position) to the positive busbar 260. The movement of the armature of the solenoid 221 first opens contacts 240, 241, 243, 244 and closes contact 247 (thus opening the above-traced indicating circuit at contact 241 and closing a retaining circuit for the solenoid 221 independent of the selector push which may now be released), and then, besides driving the selector 220 to its first half-notch position, closes contacts 242, 245, 246 and opens contact 248. Contacts 245, 246 prepare the circuit for the release relay 223 to be referred to shortly, and contact 248 deenergizes the first motion solenoid 221, the control station equipment now remaining locked against further operation with the selector in its half-notch position until the reception of a release current from the substation. The closing of contact 242 completes the circuit for the transmission of a selecting current to the substation, this circuit being taken from the control station positive busbar 260 through the contacts 326, 309, 295, 285, 254, the pilot wire A⁴, the contacts 54, 127, 136, the substation polarized relay 100, the contact 53, the pilot wire A³ and the contacts 253, 242 to the negative busbar 261. The polarity of this current is such as to operate the polarized relay 100 in the selecting direction to close its contacts 101 and energize the selector relay 90. This relay 90 again breaks the indicating circuit at contact 93 and closes contact 92 to energize the substation selector solenoid 21. The movement of the solenoid armature then drives the substation selector to its new position, and when this position is reached opens contacts 23, 25 and closes contacts 22, 24. This completes the release circuit from the substation negative busbar 61 through the contacts 22, 51, F¹, the pilot wire A¹, the contacts f¹, 251, 281, 291, 301, 245, the polarized release relay 223, the contacts 246, 273 (closed if the selecting push has meanwhile been released), the contacts 322, 306, 292, 282, 252, f², the pile wire A² and the contacts F², 52, 24 to the positive busbar 60. Thus provided the selecting push 270 has been released, the release relay 223 is energized to close its contacts 224 and energize the second motion solenoid 222. The consequent upward movement of the armature of the solenoid 222 prepares the pawl and ratchet mechanism for driving the selector through its second half-notch movement and also opens contact 242 to break the selecting circuit and thereby to deenergize the substation polarized relay 100 and the selector relay 90. This restablishes the indicating circuit at the substation end at contact 93 and deenergizes the substation selector solenoid 21, whose mechanism resets and opens contacts 22, 24 closing contacts

23, 25. The opening of contacts 22, 24 breaks the release circuit and consequently deenergizes the release relay 223 and the second motion solenoid 222, whose armature moves back under the action of a spring and drives the selector through its second half-notch movement, resetting contacts 240, 241, 243, 244, 245, 246, 247, 248. The whole system is now at rest in the new selected position with the indicating circuit completed to give a supervisory indication of the newly selected circuit-breaker.

If, instead of performing a single selecting movement, the operator wishes to perform an express selecting movement through a series of selector positions, the only difference in the above operation will be that the selecting push 270 will be depressed and rotated instead of depressed and released. This rotation of the push causes contact 272 to close, so that the release circuit is complete at the appropriate stage without the necessity of releasing the push to close contact 273. The whole selecting movement will thus be carried out as above described, but at the end a new selecting movement will automatically be started immediately the indicating mechanism closes the contact 205, since the selecting push contact 274 is held closed. Thus the selectors will automatically continue to step round from position to position giving the desired supervisory indication in each position, until the operator releases the selecting push 270 when the selecting movement in progress at the time will be completed and the system will come to rest in the desired selected position with the supervisory indicating circuit complete.

In any selected position the operator may if he wishes transmit an executive current to cause the performance of some operation on the selected apparatus at the substation. Thus if the selected apparatus happens to be an open circuit-breaker, he may depress his close push 290 to effect closing of the circuit-breaker, or if the selected circuit-breaker is closed depression of the trip push 280 will cause it to be tripped. The manner in which operation of the trip and close pushes causes the desired operation to be performed will now be described. The contacts of the two pushes are similarly arranged and the effect of depressing either of them is to open the first, second and fourth pilot wires A¹ A² A⁴ at contacts 281, 282, 285 or 291, 292, 295, thus breaking the indicating circuit, and to connect the third and fourth pilot wires A³ A⁴ to the two poles of the control station battery at contacts 283, 284, or 293, 294. This energizes the substation polarized relay 100 with a polarity opposite to that of the selecting currents over a circuit from the control station negative busbar 261 through the contacts 244, 284 (or 294), 254, the pilot wire A⁴, the contacts 54,

127, 136 the polarized relay 100, the contact 53, the pilot wire A^3 , and the contacts 253, 283 (or 293), 243, to the positive busbar 260. The polarized relay 100 consequently closes 5 its contacts 102 and energizes the executive relay 80. If the selected circuit-breaker happens to be open (the operation of the executive relay 80 then being due to the depression of the close push 290), the executive relay 10 makes its own retaining circuit at contact 85, and at contact 84 makes the energizing circuit for the trip relay 140 or the close relay 145 as the case may be, these relays in turn effecting the tripping or closing of the selected circuit-breaker in the manner above described. Release of the trip or close push at the control station then reestablishes the indicating circuit, whereby the control station operator is advised as to whether or not 20 the executive function has been correctly performed.

The establishment of the metering circuit in any selected position (other than the normal zero position) is initiated by rotation of the 25 meter switch 300 through 180° . This first opens the indicating circuit at contact 306 and thus deenergizes the auxiliary indication relay 130 which closes its contact 131. When the meter switch reaches the 90° position contact 303 closes momentarily. This completes 30 a circuit (assuming for example that the circuit-breaker associated with the selected position is closed) from the substation negative busbar 61 through the auxiliary switch 18, the selector contacts 46, the indicating busbar 76, the contacts 93, 127, 54, the pilot wire A^4 , the contacts 254, 285, 295, 309, 326, the auxiliary meter relay 310, the contacts 303, 45 51, 23, 131, 123, the first meter relay 110 and the contacts 124, 31, 45, 17 to the positive busbar 60. This at once operates the auxiliary meter relay 310 to energize the electromagnetic locking device 315 and also energizes 50 the first meter relay 110. At the expiration of its brief time-lag this relay operates its contacts. The closing of the contact 115 energizes the second meter relay 120 which retains itself at contact 128 and opens contacts 55 123, 124, 127 in the energizing circuit of the first meter relay 110, which however, remains energized owing to the closing of its contacts 112, 113, 116. The electromagnetic locking device 315 at the control station has 60 meanwhile unlocked the meter switch 300 and the continuation of the movement of this switch past the 90° position opens contact 303 and thereby deenergizes the auxiliary meter relay 310 and the substation first meter relay 110. The opening of contact 116 breaks the connection between the polarized relay 100 and the pilot wire A^4 , contact 127 now being open, and the closing of contact 117 in series with contact 129 (now closed) connects the release meter relay 135 across the

70 pilot wires A^2 A^3 in preparation for the opening of the meter circuit later. The closing of contact 111 in series with contact 121 (now closed) prepares the metering circuit at the substation end, and the completion of the movement of the meter switch 300 into the 180° position establishes the metering circuit at contact 308. This metering circuit is taken from one side of the selected metering source 19 through the metering busbar 77, the contacts 81, 151, 111, 121, 53, the pilot wire A^3 , the contacts 253, 308, the busbar 262, the selected meter 265, the selector contacts 233, the busbar 260, the contacts 326, 309, 295, 285, 254, the pilot wire A^4 , the contact 54, the metering busbar 78 and the selector contacts 47 to the other side of the metering source 19. It will be noted that the meter switch contact 302 is closed at this stage for general alarm purposes as will be explained later.

75 When the meter switch 300 is rotated further, in order to open the metering circuit, its first action is to disconnect the control station meter 265 from the pilot wires at contacts 308, 309, and it then momentarily closes contacts 305, 307 to send a current over the pilot wires A^2 , A^3 for the energization of the release meter relay 135, this circuit being taken from the control station positive busbar 260 through the contacts 243, 307, 253, the 95 pilot wire A^2 , the contacts 53, 117, 129, the release meter relay 135, the contacts 52, F^2 , the pilot wire A^2 , and the contacts f^2 , 252, 305, 244 to the negative busbar 261. The release meter relay 135 makes its own retaining circuit at contact 137 and again breaks the connection of the polarized relay 100 to the pilot wire A^4 , whilst the opening of the contact 138 breaks the retaining circuit for the relay 120 which is consequently deenergized. This 100 reestablishes the normal conditions in the selected position in the substation (except for the deenergization of the release meter relay) and the completion of the movement of the meter switch to its 360° position performs the corresponding function at the control station, and also breaks the circuit to the release meter relay, so that the whole system 105 is now again at rest in the selected position with the indicating circuit closed.

110 Telephone communication can be established between the two stations when the system is at rest in the normal zero position. If the control station operator wishes to call up the substation he lifts his telephone instrument and thereby operates the telephone dummy push 320. This first breaks the second and fourth pilot wire circuits at contacts 322, 326, and then momentarily closes contacts 324, 325 to transmit a current similar 115 to the executive currents to the control station, its final movement closing contact 323 and reclosing contact 326. The momentary executive current energizes the substation polarized relay 100 in a direction to close its 120

125

130

contacts 102 and thereby to energize the executive relay 80. The closing of contact 83 energizes the second meter relay 120 over a circuit including the selector contacts 35 closed only in the normal zero position. This relay 120 makes its own retaining circuit at contact 128 as before, so that it remains energized when the executive relay is deenergized as the result of the deenergization of the polarized relay 100 when contact 127 opens, and the closing of contact 129 prepares the circuit for the release meter relay 135. The contact 121 on the second meter relay 120 prepares the metering circuit for the transmission of the telephone speaking currents, and the contact 122 closes a circuit to the substation telephone call bell 162 through the hook switch 161 and the selector contacts 36. When the substation operator responds to the call and lifts his receiver, the hook switch 161 breaks the calling circuit and the speaking circuit is now complete, this circuit extending from the substation telephone 160 through the contacts 81 (now again closed), 151, 111, 121, 53, the pilot wire A³, the contacts 253, 323, 341, the control station telephone 330, the contacts 326, 309, 295, 285, 254, the pilot wire A⁴, and the contacts 54, 37 back to the substation telephone. When the call is finished the control station operator replaces his instrument and the dummy push is released, first opening contacts 323, 326, then closing and opening contacts 321, 324 and finally closing contacts 322, 326. The momentary closing of contacts 321, 324 sends a current over the pilot wires A² A³ to energize the release meter relay 135 and thereby to deenergize the second meter relay 120, the whole system then returning to its normal condition.

If the substation operator wishes to call up the control station when the system is in the zero position, he depresses his telephone push 165. This causes a current similar to a circuit-breaker-closed indicating current to be transmitted over the indicating circuit, the connection from the indicating busbar 75 to the auxiliary indication relay 130 however being taken through the contacts 32, 166 instead of through the contacts 31, 124. The polarized relay 200 at the control station is thus energized to close its contacts 201 and energize the coil 210, thereby closing the circuit to the buzzer 331 at contact 212. On responding to the call, the control station operator lifts his instrument and operates the substation call bell in the manner above described, whereupon the substation operator lifts his receiver and communication is established.

The general alarm arrangements will now be described first of all with reference to the transmission of a general alarm signal when a change of condition of one of the substation apparatus occurs automatically while the

system is at rest in the normal zero position. When such a change occurs the flick switch 16 on the circuit-breaker which has operated (or an equivalent device in the case of other substation apparatus) closes momentarily and energizes the substation general alarm relay 150 over a circuit including the selector contacts 44 and the general alarm bus-bar 70. This relay at once makes its own retaining circuit at contact 154, which is in series with the contact 157 of the definite time limit relay 156. This relay 156 is simultaneously energized by the closing of contact 153. The closing of contact 152 causes a current similar to a circuit-breaker-opening indicating current to be transmitted over the indicating circuit, the connections of the substation battery to the indicating busbars 75, 76 being taken through the telephone push contacts 167, 168 and the selector contacts 33, 34, whilst the connection from the busbar 75 to the auxiliary indication relay 130 is taken through the contacts 32, 152. The auxiliary indication relay 130 and the polarized relay 200 at the control station are thus both energized, the latter in a direction to close its contacts 202 and energize the coil 215. The operation of the auxiliary indication relay 130 completes another circuit from the indicating busbar 75 to the control station through the contacts 155, 132, 23, 51, F¹, the pilot wire A¹, the contacts f¹, 251, 281, 291, 301, 218 (closed by operation of the coil 215) the control station general alarm relay 350 and the contact 240, this circuit being in parallel with the previously traced portion of the indicating circuit including the pilot wire A² and the polarized relay 200. Thus the operation of the substation general alarm relay 150 in the normal zero position causes the energization both of the control station general alarm relay 350 and of the control station polarized relay 200. The former relay energizes the auxiliary general alarm relay 355, which retains itself at contact 357 through the stop alarm push contact 337 and the auxiliary reindication relay contact 365 and also completes at contact 356 the circuit to the buzzer 331 and red lamp 332. The closing of contact 217 energizes the general reindication relay 370, which makes its own retaining circuit at contact 372 through the selector contacts 230 closed in the first four selector positions, and also energizes the auxiliary reindication relay 360 at contact 371. This latter relay makes at contact 361 its own retaining circuit which passes either through the contacts 271, 336 on the selecting and stop alarm pushes or through the selector contacts 232. The closing of contact 362 makes a further energizing circuit for the buzzer 331 and the opening of contact 365 breaks the retaining circuit for the auxiliary general alarm relay 355 (whose main energizing circuit is however still complete.) The contacts 373, 374 on the general rein-

dition relay bridge the selecting push contacts 273, 274 and consequently the operation of this relay starts an express selecting and indicating cycle, the general alarm relays 350, 5 355 being deenergized as soon as the cycle starts. The retaining circuit for the general reindication relay 370 is broken after the selectors pass the fourth position, but the control of the express selecting cycle has meant 10 while been taken over by the contacts 363, 364 on the auxiliary reindication relay in series with the cam-operated contacts 227, 228. The cycle therefore proceeds to enable the indicating mechanism to give a record of the 15 condition of the substation apparatus, whereby when the operator responds to the alarm signal he can see at once what change has occurred to cause the alarm. When the cycle is complete and the normal zero position 20 again reached, the cam-operated contacts 227, 228 open and stop the cycle, but the auxiliary reindication relay still remains energized over the circuit including the stop alarm push contact 336 and the selecting push 25 contact 271, so that the buzzer continues to sound. Depression of either of these pushes will stop the buzzer and the operator can take what steps he thinks fit to deal with the situation, the system now being at rest in its 30 normal condition. It should be mentioned that the substation general alarm relay 150 has meanwhile been deenergized owing to the breaking of its retaining circuit at contact 157 at the expiration of the time lag of the 35 relay 156.

If now the change of condition occurs when the selectors are at rest in any selected position other than the normal zero position, the operation of the flick switch 16 on any 40 circuit-breaker other than the selected circuit-breaker will energize the general alarm relay 150. This exception is made in view of the fact that it is not desirable to initiate a general alarm signal when the change of 45 condition results from the transmission of an executive current from the control station, whilst if the change occurs automatically when the circuit-breaker is actually selected, the indicating circuit will be complete and 50 the change will be at once apparent without an alarm signal. The operation of the general alarm relay 150 in this case will cause current to flow over the first pilot wire circuit to the control station general alarm relay 55 350 (one or other of the contacts 213, 218 and also the contact 181 being closed owing to the indicating currents flowing at the time) but the parallel circuit over the second pilot wire to the polarized relay 200 will not in this 60 case be made owing to the fact that the selector contacts 32 are open. The control station general alarm relay 350 will act through its self-retaining auxiliary relay 355 to complete the buzzer circuit, but will itself be de- 65 energized as soon as the definite time limit

relay 156 breaks the retaining circuit to the substation general alarm relay 150.

A generally similar operation occurs in the event of a general alarm signal being initiated whilst metering is in progress. Provision is made for the initiation of this signal by the automatic operation of the circuit-breaker associated with the selected position as well as by the operation of any other circuit-breaker. For this purpose the selector contacts 43 are provided and the general alarm relay 150 is then energized through these contacts and the auxiliary general alarm busbar 71, the circuit also including the second meter relay contact 126 (now closed). If the metering source in any position happens to be closely associated with the circuit-breaker in the same position, an automatic change may be readily apparent from the movements of the meter pointer, and in such cases the selector contacts 43 may be omitted so that a general alarm signal is not transmitted during metering in such a position if due to a change in the condition of the associated circuit-breaker. It will be appreciated that, when metering is in progress, since no indicating currents are flowing the auxiliary indication relay 130 and the control station polarized relay 200 are both deenergized and the previously described circuit to the control station general alarm relay 350 through the first pilot wire A¹ is broken at both ends. This difficulty is obviated at the substation end by the provision of the contact 125 on the second meter relay 120 and at the control station end by the provision of the contact 302 on the meter switch 300. Thus when the substation general alarm relay 150 is energized during metering, its contact 151 breaks the metering circuit, and its contact 155 completes a connection from the indicating busbar 75 through the contacts 125, 23, 51, F¹, the pilot wire A¹ and the contacts f¹, 251, 302, to the control station general alarm relay 350, the remainder of this circuit being as previously traced. Thus the control station buzzer will sound, and the general alarm relay will be deenergized after the time interval determined by the definite time limit relay 156.

It should be mentioned that, since the energizing circuit of the relay 156 includes the contacts 114, 91 and 82 (so that this relay is not energized whilst the first meter relay or the selector relay or the executive relay is functioning), the time limit for deenergization of the general alarm relay does not commence until such functions have been completed. The time limit of the relay is chosen long enough to allow time for the general alarm apparatus at the control station to operate.

It now remains to describe the effect of the temporary borrowing of the first and second pilot wires A¹ A² for protective purposes in

the various conditions of the remote control system. As mentioned above, the tripping and stabilizing relays E F *e f* at the two ends of the protected feeder B are energized independently and consequently may not operate exactly simultaneously. There are therefore three possible cases to be considered, namely the simultaneous disconnection of the two pilot wires A¹ A² at both ends, the momentary energization of the pilot wires from the protective battery *h* at the control station end owing to the operation of the tripping and stabilizing relays *e f* at that end before the tripping relay F at the substation end, and the momentary energization of the two pilot wires from the protective battery H at the substation end owing to the operation of the tripping and stabilizing relays E F at that end before the tripping relay *f* at the control station end.

If the protective apparatus operates when the remote control system is in its normal zero or general alarm position, no harm can arise from the temporary disconnection of the first and second pilot wires A¹ and A² since no currents are flowing therein. Moreover since the first pilot wire circuit is broken at the control station at contacts 213, 218 when the polarized relay 200 is deenergized, the energization of these pilot wires from the substation protective battery H will have no effect. At the substation end, however, there is a complete circuit across the two pilot wires A¹ A² including the auxiliary indication relay 130 and the first meter relay 110. Consequently during the very short interval in which the protective battery *h* at the control station could be connected across these pilot wires, a current would flow in this circuit which would operate the auxiliary indication relay 130 and break the circuit to the first meter relay at contact 131, the auxiliary indication relay perhaps being energized and deenergized a few times. Since however this relay is quick-acting and the first meter relay has a short time-lag, no harmful effect can be produced on the remote control system.

In the case when the remote control system is at rest in a selected position other than the general alarm position with the indicating currents flowing, the only effect of the temporary disconnection of the two pilot wires A¹ and A² will be to suspend the flow of indicating currents until the protective gear has operated and reestablished the remote control circuits. At the control station while indicating currents are flowing there is a complete circuit across the first and second pilot wires A¹ A² through the general alarm relay 350, but current cannot flow in this circuit from the substation protective battery H, since prior to the connection of the battery to the pilot wires A¹ A², these wires must be disconnected, as a result of which the control station polarized relay 200

will be deenergized and will open the first pilot wire circuit at contact 213 or 218 before current can flow to the general alarm relay 350. At the substation end the conditions will be the same as for the general alarm position.

If now the protective gear borrows the pilot wires A¹ A² during the selecting process after the first half-notch movement is completed, i. e. when the release relay 223 is connected across the first and second pilot wires A¹ A², the temporary disconnection of these pilot wires from the remote control system will delay the completion of the selecting movement but will not have any other harmful effect. As previously mentioned the release relay is polarized so that it remains unaffected by any currents passing through it from the substation protective battery H. At the substation, the condition of the first and second pilot wires is at first the same as in the general alarm or other selector position, but when the substation selector 20 has completed its movement, the substation battery 50 will be connected across the two pilot wires through the contacts 22, 24. Thus it may happen that the substation remote control battery 50 and the control station protective battery *h* are momentarily connected directly to oppose one another over a circuit including only the two pilot wires A¹ A², but this will have no harmful effect if the two batteries are suitably chosen.

The performance of an executive function is confined wholly to the third and fourth pilot wires A³ A⁴ and remains unaffected by the operation of the protective gear.

In the case when a metering circuit is established, the operation of the protective gear will similarly have no effect for the metering circuit includes only the third and fourth pilot wires A³ A⁴ and there is no complete circuit at either end across the first and second pilot wires A¹ A². Thus at the substation the second meter relay holds the first pilot wire circuit open at contacts 123, 125 and at the control station the meter switch holds the second pilot wire circuit open at contacts 305, 306.

If it should happen that the protective gear operates during the process of establishing a metering circuit whilst the meter switch 300 is in its 90° position, the temporary disconnection of the two pilot wires A¹ A² will break the circuit of the auxiliary meter relay 310 and the first meter relay 110. If this occurs before the expiration of the time-lag of the first meter relay 110 and of the electromagnetic lock 315, the effect will be to deenergize the relays 110, 310 and leave the meter switch locked in the 90° position. The normal process will continue immediately the protective gear restores the pilot wires. If the disconnection of the pilot wires occurs after the expiration of the time-lag, the first

meter relay 110 will be temporarily deenergized, but the second meter relay 120 will remain energized. The meter switch 300 will continue to rotate to the 180° position since 5 the lock is held released over the retaining circuit including contacts 304, 317, and the metering circuit will be established when the pilot wires are restored.

For the case of operation of the protective 10 gear during release metering operations when the meter switch is in the 270° position, the only possible interference is from the temporary disconnection of the second pilot wire circuit, since the first pilot wire circuit 15 is at this stage open at both ends. In order to prevent failure to energize the release meter relay 135 owing to protective interference, the time during which the contacts 305, 307 remain closed during rotation of the 20 meter switch is arranged to be greater than the longest time of interference from the protective gear. This ensures that there will be at least a momentary transmission of current 25 either before or after the protective operation, and since the release meter relay 135 is a quick-acting relay, such momentary current will in any event be sufficient to ensure its operation.

From the cases above described it will also 30 be clear that the temporary borrowing of the first two pilot wires for protective purposes will not have any harmful effect during other conditions of the remote control system, such for example as when telephone or 35 general alarm currents are flowing.

It will be appreciated that the arrangement above described has been given by way of example only and may be modified in various ways within the scope of the invention. 40 Thus for instance the particular allocation to the individual pilot wires of the various remote control functions above described, may be departed from to some extent provided that any rearrangement does not involve 45 harmful interference with the remote control system when the two pilot wires are borrowed for protective purposes. Again the above arrangement has been described primarily with the use of a protective system arranged according to the prior United States 50 Patent No. 1,765,887 above referred to, but it will be appreciated that other forms of protective system requiring the use of two pilot wires may be substituted therefor, if necessary, with consequent detail alterations 55 in certain parts of the remote control apparatus.

What we claim as our invention and desire to secure by Letters Patent is:—

60 1. A combined remote control and protective system for the selective remote control from a control station of apparatus units at an electric power substation and for the protection of a feeder or like circuit lying adjacent to such system, including in combina-

tion four pilot wires connecting the two stations and normally forming part of the remote control system two of the pilot wires being capable of being borrowed for protective purposes when required, a D. C. 70

source of E. M. F. associated with the protective system at each end, a transfer device at each end of the protective system, means whereby each transfer device when operated

75 by the protective gear acts to disconnect the two borrowable pilot wires from the remote control system at the adjacent end, means whereby either transfer device may act in accordance with the protective requirements

80 to connect the borrowable pilot wires to the adjacent protective source of E. M. F., apparatus at the control station for transmitting selecting currents over the two unbor- 85 rowable pilot wires to the substation, a selec- 90 tor at the substation to which step-by-step movements can be imparted for the suc- 95 ccessive selection of individual apparatus units, a D. C. source of E. M. F. in the substation associated with the remote control system, means at the substation acting in response to a selecting current to cause the selector to 100 perform one stepped movement, means whereby on completion of such movement the selector causes the remote control source of E. M. F. to be connected to the two bor- 105 rowable pilot wires with a polarity opposite to that with which the adjacent protective source of E. M. F. can be connected to such pilot wires, means whereby the control station apparatus for transmitting the selecting currents remains locked against further operation after a selecting current has been transmitted, and a polarized release relay in the control station unresponsive to current received over the borrowable pilot wires from the protective source of E. M. F. but acting when energized by the current trans- 110 mitted from the remote control source of E. M. F. on completion of the selector move- 115 ment to unlock the control station apparatus.

2. An electric selective remote control system for a number of circuit-breakers or other apparatus units at an electric power substation, including in combination four pilot wires connecting the substation and the control station of which two are retained exclusively for remote control purposes whilst the other two normally serve for remote control

115 purposes but are available for temporary bor- 120 rowing for other purposes, means for discon- 125 necting the two borrowable pilot wires from the remote control system when required for such other purposes and for returning them to their normal remote control connections when no longer so required, apparatus at the control

125 station for transmitting selecting currents over the two unborrowable pilot wires to the substation, a selector device at the substation acting in response to the selecting currents to

130 select individual apparatus units, means

- whereby when an apparatus unit is selected a current for indicating the condition of the selected unit is transmitted to the control station over one of the borrowable pilot wires 5 and one of the unborrowable pilot wires, an indicator device at the control station responsive to the indicating currents, an alarm apparatus at the substation operative in the event of a change occurring automatically in 10 the condition of the controlled apparatus units, an alarm apparatus at the control station associated with the substation alarm apparatus, and devices operative while the indicating currents are flowing in the one borrowable pilot wire to prepare an alarm circuit including the other borrowable pilot wire over which the substation alarm apparatus can transmit current for the energization of 15 the control station alarm apparatus.
- 20 3. An electric selective remote control system for a number of circuit-breakers or other apparatus units at an electric power substation, including in combination four pilot wires connecting the sub-station and the control station, apparatus at the control station for transmitting selecting currents over the third and fourth pilot wires to the sub-station, a selector device at the sub-station acting in response to the selecting currents to 25 select individual apparatus units, means whereby when an apparatus unit is selected a current for indicating the condition of the selected unit is transmitted to the control station over the second and forth pilot wires, 30 an indicator device at the control station responsive to the indicating currents, an alarm apparatus at the sub-station operative in the event of a change occurring automatically in the condition of the controlled apparatus 35 units, an alarm apparatus at the control station associated with the sub-station alarm apparatus, an auxiliary relay connected in series with the second pilot wire at the sub-station and acting while the indicating currents are 40 flowing to prepare an operative connection from the sub-station alarm apparatus to the first pilot wire, means associated with the indicator device at the control station for connecting the control station alarm apparatus 45 to the first pilot wire while the indicating currents are flowing, and means whereby the operation of the sub-station alarm apparatus while the indicating currents are flowing causes the completion of an alarm circuit over 50 the first and fourth pilot wires for the energization of the control station alarm apparatus.
4. The combination with the features set forth in claim 3, of a protective system for a feeder or like circuit lying adjacent to the remote control system, and devices operated by the protective gear whereby the first and second pilot wires are transferred when required from the remote control system to the protective system and are returned to their normal 55 remote control connections as soon as their services are no longer required for protective purposes.
5. The combination with the features set forth in claim 2, of a protective system for a 70 feeder or like circuit lying adjacent to the remote control system, a source of E. M. F. associated with the protective system at each end, a transfer device at each end of the protective system, means whereby each transfer device when operated by the protective gear 75 acts to disconnect the two borrowable pilot wires from the remote control system at the adjacent end, means whereby either transfer device may act in accordance with the protective requirements to connect the borrowed pilot wires to the protective source of E. M. F. at the adjacent end, and means whereby the devices operative to prepare the alarm circuit act on the disconnection of the borrowable pilot wires at either end to break 80 the alarm circuit and thereby to prevent inadvertent energization of the control station alarm apparatus from the protective source of E. M. F.
6. An electric selective remote control system for a number of circuit-breakers or other apparatus units at an electric power substation, including in combination four pilot wires connecting the substation and the control station of which two are retained exclusively for remote control purposes whilst the other two normally serve for remote control purposes but are available for temporary borrowing for other purposes, means for disconnecting the two borrowable pilot wires 90 from the remote control system when required for such other purposes and for returning them to their normal remote control connections when no longer so required, 95 apparatus over the control station for transmitting selecting currents over the two unborrowable pilot wires to the substation, a selector device at the substation acting in response to the selecting currents to select individual apparatus units, means whereby 100 when an apparatus unit is selected a current for indicating the condition of the selected unit is transmitted to the control station over one of the borrowable pilot wires and one of the unborrowable pilot wires, an indicator 105 device at the control station responsive to the indicating currents, at least one metering source in the substation, at least one meter in the control station which can be connected to the corresponding substation metering source 110 over a clean circuit including the two unborrowable pilot wires, means at the control station for transmitting an initiating current to the substation over one unborrowable pilot 115 wire and the borrowable pilot wire other than that utilized for the indicating circuit, a time-lag relay in the substation acting in response to the initiating current to connect the substation metering source to the two unborrowable pilot wires, and a quick-acting 120 125 130

relay at the substation which is connected in series with the borrowable pilot wire utilized for carrying the indicating current and acts whenever current is flowing in such pilot 5 wire to disconnect the other borrowable pilot wire from the time-lag relay.

7. The combination with the features set forth in claim 6, of means whereby the control station apparatus for transmitting the 10 initiating current to the time-lag relay is held locked in the event of temporary disconnection of the borrowable pilot wires before the completion of the time-lag of the relay, whereby the normal process of energizing such relay recommences immediately the 15 pilot wires are reconnected.

8. The combination with the features set forth in claim 6, of means whereby the control station apparatus for transmitting the 20 initiating current performs the further operation after such current has been transmitted of connecting the meter to the unborrowable pilot wires, an electro-magnetic locking device normally acting to prevent the 25 performance of such further operation, an auxiliary relay at the control station responsive to the initiating current, and means whereby such auxiliary relay acts to release the locking device after a time-lag corresponding to that of the substation time-lag 30 relay.

9. A combined remote control and protective system for the selective remote control from a control station of apparatus units 35 at an electric power substation and for the protection of a feeder or like circuit lying adjacent to such system, including in combination four pilot wires connecting the two stations and normally forming part of the remote control system, two of the pilot wires 40 being capable of being borrowed for protective purposes when required, a source of E. M. F. associated with the protective system at each end, a transfer device at each end 45 of the protective system, means whereby each transfer device when operated by the protective gear acts to disconnect the two borrowable pilot wires from the remote control system at the adjacent end, means whereby 50 either transfer device may act in accordance with the protective requirements to connect the borrowable pilot wires to the adjacent protective source of E. M. F., a time-lag relay connected between the two borrowable pilot 55 wires at the substation and controlling the performance of a remote control function at that station, means at the control station for transmitting a current for the energization of such time-lag relay, and means for preventing inadvertent operation of the time-lag relay resulting from the temporary connection thereof to the protective source of 60 E. M. F. comprising a quick-acting relay connected in series between one borrowable pilot wire and the time-lag relay and acting 65

when energized to break the connection between the other borrowable pilot wire and the time-lag relay.

10. The combination with the features set forth in claim 9, of means whereby the control station apparatus for transmitting current for the energization of the time-lag relay is held locked in the event of the temporary disconnection of the borrowable pilot wires before the completion of the time-lag 75 of the relay, whereby the normal process of energizing such relay recommences immediately the pilot wires are reconnected.

In testimony whereof we have signed our names to this specification.
